MULTI-PIECE PLASTIC WATER CLOSET BOWL
Louis Witvrouw, 51 Ave. Hanlet,
Heusy-lez-Verviers, Belgium
Filed Mar. 17, 1961; Ser. No. 96,454
Claims priority, application Belgium Mar. 18, 1960
5 Claims. (Cl. 4—69)

The invention relates to a simple and economic process for the manufacture of a water closet basin in plastic material.

Actually the production of such a basin is extremely difficult owing to the complexity of the form which implies very costly moulds. On the other hand, in different sanitary installations the position of the outlet pipe varies according to the installation and therefore necessitates in each case a basin of which the emplacement of the outlet pipe must be appropriate to the emplacement of the said fall pipe; it is therefore necessary to have a very extensive range of basins having the same form but with different outlet pipes. The tooling required for the manufacture of water closet basins should therefore, up to present, comprise as many moulds as there are different outlet pipes.

In order to remedy this disadvantage the process of manufacture according to the invention consists in making a basin in plastic material by having a number of moulded elements each in one piece and which can be assembled on horizontal planes.

According to one advantageous form of the invention, the manufacture of such a basin consists in making by moulding four elements, as a maximum, and in assembling them by sticking them together or the like on a horizontal plane, the first element forming the upper rim of the basin with its supply pipe, the second element with internal directing walls forming the bowl of the basin, its upper edge being housed and fixed, for example by sticking, in a housing provided on the lower edge of the first element, while its lower edge is housed and fixed in an external junction moulding forming a part of the third element, which forms with a second element a siphon, all resting by its moulding junction on the fourth element forming the base of the assembly or pedestal of the basin.

According to another characteristic of the invention, the element forming the pedestal of the basin has three outlet orifices, of which one is arranged laterally on a horizontal axis and the other two are side by side in the base of the pedestal on vertical axes, these three orifices being moreover with advantage closeable if desired by a similar corresponding type of sealing plug.

According to a further object of the invention, the water closet basin is fixed to the floor by means of a supporting base, preferably in plastic material, of internal dimensions corresponding to those of the pedestal of the basin, giving on the one hand holes for the introduction of screws to fix it to the floor and on the other hand threaded pegs projecting vertically on the upper part of the said body and inserted into the holes made in the pedestal of the basin in order to receive fixing nuts, capped or the like.

The invention will now be described in more detail by way of example, with reference to the accompanying drawings in which:

FIGURE 1 is a profile view of the improved water closet basin;

FIGURE 2 is a vertical longitudinal section across the basin;

FIGURE 3 is a vertical section on the line III—III of FIGURE 2;

FIGURES 4 and 5 are two views similar to FIGURE 1,

2

with section in the pedestal showing two outlets which can be arranged with the same basin;

FIGURES 6 and 7 are a plan view and a profile view of the supporting base for fixing the base to the floor;

FIGURE 8 is a profile view of the basin mounted on its supporting base.

As is seen in particular in FIGURES 1 to 3 of the attached diagrams, the production of a water closet basin in plastic material according to the invention consists in making, by moulding, four elements: a rim 1, a bowl 2, an intermediate piece 3 forming a siphon with the element 2, and a pedestal 4, each in one piece, and in assembling them, by sticking together or the like, on horizontal planes.

The rim 1 is provided at its rear part with a supply pipe 5 moulded with the said rim and also on all its lower circumference with a groove 6 of appropriate dimensions, while the element 2 is profiled in the form of a bowl terminating at the rear in a vertical tubulure 7.

The element 3 is formed at the rear of another bowl 8 into which opens the said tubulure 7, and at the front by a vertical tubulure 9, a moulding in the form of a double groove 10 being provided over all of its periphery.

The pedestal 4 forming the base of the assembly has three outlet orifices of which one, marked 11 on the diagram, is arranged on a horizontal axis in the rear part of the said pedestal and the two others marked 11' and 11'', are on vertical axes in the part forming the base of the said element. These orifices, of circular section, have towards the inside a part 12, or 12' or 12'', in the form of a section of cone and a tubular part 13, or 13' or 13'', projecting to the outside.

The assembly of these four elements, of which the manufacture by moulding offers no difficulty owing to the fact that each element is easily moulded in one piece, is brought about with the aid of the suitably arranged grooves 6 and 10. Actually the upper edge 2' of the elements 2 fits, and is fixed by sticking, in the groove 6 of the element 1, while its lower edge fits and is fixed in its turn in the upper part of the double groove 10, the lower part of which receives the upper edge 4' of the element 4.

When thus assembled, the water closet basin according to the invention has internally a siphon formed by the assembly of the elements 2 and 3, the tubulure 7 dropping to midway in the bowl 8 serving as entry tubulure and the discharge tubulure 9 emptying into the element 4.

A water closet basin made in this way can serve equally, according to the installation, for a discharge pipe at the rear or for a discharge pipe central or offset in the base. According to the application, the two orifices which are not used are closed by sealing plugs such as shown at 14 in FIGURE 4, while the outlet orifice is provided either for the base, with an adaptor such as 15, or for the rear wall with an adaptor such as 16 (FIGURE 5) in the form of a 90° elbow. The latter may be able to rotate by a half circle with respect to the basin in order to allow of its fixing according to the orientation of the fall pipe, and it is provided with a tubulure 17 connected to a ventilation pipe. This piece 16 can be replaced by a piece 18 (FIGURE 1) in the form of a straight tube also provided with a tubulure 17, projecting at 90°, and also capable of describing a rotation on its axis in order to allow of its fixing according to the orientation of the ventilation piping. In the case of an outlet at the base of the basin, the plug 14 placed on the lateral orifice 11 may be provided with a perforation for fitting to the ventilation pipe.

The placing of the plugs 14 and of the adaptor 15 is done at the time of assembly of the four elements,

while the adaptors 16 and 17 are mounted on the basin by the sanitary engineer.

As was stated at the start of this specification, another object of the invention is to produce a supporting base in order to facilitate the fixation of the water closet basin to the floor. This supporting base, marked 19 in FIGURES 6 to 8, preferably in plastic material, of a form which is substantially rectangular and of dimensions adapted to the internal dimensions of the pedestal of the basin, is pierced with four holes 20 for the introduction of screws, such as 21, intended for fixing the base to the floor, and surmounted by four threaded pegs 22 projected vertically on the upper face of the said base and intended to be introduced into the holes provided for this purpose on the base of the pedestal, the said pedestal being kept on the said pegs by capped nuts 23. The internal edges of the base have reference marks 24 corresponding to the outlet orifices of the basin. This form greatly facilitates the placing of the basin since it is sufficient, starting for example with a central discharge pipe 25 shown in FIGURE 6 as dotted lines, to make the two axes A—A and B—B of this pipe coincide with the appropriate reference marks 24 of the base. The latter is then fixed to the floor in the desired position by the screws 21, and it is only necessary to place the basin on the base and to screw up the screws 23, the central outlet orifice corresponding exactly to the discharge pipe.

The manufacture according to the invention of a water closet basin in plastic material has been described above with reference to the attached diagrams starting from four main elements, but it is of course understood that it is not a departure from the sphere of the invention to make such a product of three elements, for example by combining the element or rim 1 with the element or bowl 2.

What I claim is:

1. As a new article of manufacture, a multi-piece water closet assembly of plastic material, comprising a hollow pedestal having a plurality of discharge openings, a syphon element provided with a first tubulure extending into said pedestal mounted on said pedestal, an open end flush bowl mounted on said syphon and provided with a second tubulure extending into said syphon forwardly of the first tubulure and a rim element for circulating water secured peripherally of the bowl's open end, said syphon element being formed with a double grooved molding adapted to receive the upper and lower edges of said pedestal and flush bowl, respectively.

2. As a new article of manufacture, a multi-piece water closet assembly of plastic material, comprising a hollow pedestal having a pair of spaced tubulures extending downwardly from its bottom, and a laterally extending tubulure, all said tubulures being of equal cross-section, a syphon element provided with a first tubulure extending into said pedestal mounted on said pedestal, an open end flush bowl mounted on said syphon and provided with a second tubulure extending into said syphon forwardly of the first tubulure and a rim element for circulating water secured peripherally of the bowl's open end, said syphon element being formed with a double grooved molding adapted to receive the upper

and lower edges of said pedestal and flush bowl, respectively.

3. As a new article of manufacture, a multi-piece water closet assembly of plastic material, comprising a hollow pedestal having a pair of spaced tubulures extending downwardly from its bottom, and a laterally extending tubulure, all said tubulures being of equal cross-section, said lateral tubulure being further provided with a connecting nipple adapted to be displaced in a desired direction, said nipple having an extension for connection to a ventilating pipe, a syphon element provided with a first tubulure extending into said pedestal mounted on said pedestal, an open end flush bowl mounted on said syphon and provided with a second tubulure extending into said syphon forwardly of the first tubulure and a rim element for circulating water secured peripherally of the bowl's open end, said syphon element being formed with a double grooved molding adapted to receive the upper and lower edges of said pedestal and flush bowl, respectively.

4. As a new article of manufacture, a multi-piece water closet assembly of plastic material, comprising a hollow pedestal having a pair of spaced tubulures extending downwardly from its bottom, and a laterally extending tubulure, all said tubulures being of equal cross-section, said lateral tubulure being further provided with a connecting nipple adapted to be displaced in a desired direction, said nipple having an extension for connection to a ventilating pipe, a syphon element provided with a first tubulure extending into said pedestal mounted on said pedestal, an open end flush bowl mounted on said syphon and provided with a second tubulure extending into said syphon forwardly of the first tubulure and a rim element for circulating water secured peripherally of the bowl's open end, said syphon element being formed with a double grooved molding adapted to receive the upper and lower edges of said pedestal and flush bowl, respectively, and a supporting frame for said pedestal, provided with inwardly disposed guides for facilitating the guidance of the water closet assembly into alignment with a discharge pipe and means for securing said pedestal to said frame.

5. As a new article of manufacture, a multi-piece water closet assembly of plastic material, comprising a hollow pedestal having a plurality of discharge openings, a syphoning device provided with a first discharge tubulure extending into said pedestal, said syphoning device being mounted on said pedestal, an open end flush bowl terminating at its lower end with a second tubulure extending into said syphoning device and a rim element for circulating water, secured peripherally about the open end of said flush bowl.
